O. H. MUELLER.

JET CONDENSER.

APPLICATION FILED DEC. 7, 1908.

1,015,822.

Patented Jan. 30, 1912.

UNITED STATES PATENT OFFICE.

OTTO HILDEBERT MUELLER, OF CAMBERWELL, ENGLAND, ASSIGNOR TO HENRY R. WORTHINGTON, A CORPORATION OF NEW JERSEY.

JET-CONDENSER.

1,015,822.

Specification of Letters Patent. Patented Jan. 30, 1912.

Application filed December 7, 1908. Serial No. 466,259.

To all whom it may concern:

Be it known that I, OTTO HILDEBERT MUELLER, a subject of the Emperor of Germany, residing at Camberwell, county of Kent, England, have invented certain new and useful Improvements in Jet-Condensers, fully described and represented in the following specification and the accompanying drawings, forming a part of the same.

10 This invention relates particularly to jet condensers of the so-called ejector type, the especial objects being to expose to the steam as large a surface of condensing water as possible, and to reduce the loss of energy 15 or power required for water circulation.

In the accompanying drawings forming a part of this specification, there is shown a condenser of the preferred form embodying the invention, and this construction will 20 now be described in detail and the features forming the invention then specifically pointed out in the claims.

In the drawings:—Figure 1 is a vertical section of the condenser cone with the water and steam distributing devices in elevation. Fig. 2 is a vertical section on the line 2 of Fig. 4. Figs. 3 and 4 are sections on respectively the lines 3 and 4 of Fig. 2. Fig. 5 is a detail section of a portion of the 30 water distributing ring, showing the adjustment for varying the condensing water. Fig. 6 is a view similar to Fig. 5 showing a modification. Fig. 7 is a section on the line 7 of Fig. 6.

35 Referring to said drawings, A is the condenser cone, B the discharge pipe to which may be attached a barometric tail pipe in a barometric condenser, C is the exhaust steam inlet, D the condensing water inlet, this 40 condensing water inlet D being formed by a pipe extending downward centrally of the condenser. At the lower end of the water inlet pipe D is the casing E provided with passages for steam and water, and ring F 45 forming an annular water chamber 12 surrounding the casing E and co-acting with the bottom edge of the casing to form an annular water jet. The casing E is supported by a flange connection 10 with the lower end of pipe D and the ring F is connected by bolted flange 11 with the casing E. The lower edge 1 of ring F with the outer edge 2 of the bottom of the casing E 50 forms a narrow opening a, through which

the annular water jet is thrown into the 55 condensing chamber from the water chamber 12, this water chamber 12 being connected by water passages 13 with the pipe D, these passages 13 being arranged in an annular series about the casing E. Between the water passages 13 are the steam 60 passages 14 passing vertically through the casing E and connecting the steam inlet C with the condensing chamber inside of the annular water jet from passage a. Steam 65 is also admitted to the condensing chamber outside of and surrounding the annular water jet through the narrow annular space or passage 15 surrounding the distributing apparatus between the ring F and the inner 70 wall of the condenser cone.

The water thrown through the passage a forms a complete cone having its apex in the narrow throat by which the condenser cone connects with the discharge pipe B, 75 and preferably is out of contact with the inner wall of the condenser cone, as shown, so as to avoid the friction resulting from the water moving in contact with the wall at the high velocity required in these 80 condensers. Loss of energy or waste of power of the circulating pump is thus avoided. It will be seen, also, that, in the preferred construction shown, the water passes downward through the condenser without substantial 85 change of direction which also avoids loss of energy and increases the efficiency of the condenser. The inside of this water cone is in contact with the steam passing through openings 14 and the outside of the cone with steam passing through the annular passage 15, so that a single water jet provides two steam condensing surfaces, and secures a large condensing surface, and the steam is preferably distributed 90 about equally on the two surfaces of the annular water jet, so as to secure the maximum condensing effect.

The edges 1, 2 of the ring F and casing E are inclined so as to throw the annular 100 jet inward in cone form, and for readily adjusting the amount of water passing through the condenser, the edges are so formed that the raising or lowering of the ring F decreases or increases the width of 105 the passage a, as shown clearly in Fig. 5. The ring F may be adjusted by any suitable means, but as shown is adjusted by putting

more or less packing 3 between the flange 11 and support on casing E to lower or raise the ring.

In some cases a larger water surface than 5 is obtainable by annular passage *a* may be desired, in which case notches *b* may be provided on one or both sides of the annular passage *a*, as shown in Figs. 6 and 7, the adjustment of the width of the annular 10 passage *a* being still retained, if desired.

What is claimed is:—

1. In a water jet condenser, the combination with a condenser cone, of a vertical injection pipe in the upper part of the condenser and terminating in a casing separated from the condenser wall and forming 15 a water chamber, an annular passage connected with the water chamber through which an annular water jet is thrown downward in the condenser cone, a steam inlet above the casing opening into the space 20

about the injection pipe and between the casing and condenser wall, and passages through the casing for the admission of steam from said steam inlet to the space 25 within the annular water jet.

2. The combination with the condenser cone and vertical injection pipe D, of casing E on the lower end of the pipe, having water passages 13, ring F forming with casing E annular water chamber 12 with which 30 said passages 13 connect and annular jet passage *a*, and vertical steam passages 14 through the casing E to the interior of the water jet, substantially as described.

In testimony whereof I have hereunto set my hand, in the presence of two subscribing witnesses.

OTTO HILDEBERT MUELLER.
